UNITED STATES PATENT OFFICE.

ABRAHAM B. GREENWALT, OF MILLERSVILLE, PENNSYLVANIA.

DESIGN FOR TOY-WHEELBARROW FRAME.

Specification forming part of Design No. **11,177**, dated May 6, 1879; application filed February 8, 1879.
[Term of patent 14 years.]

To all whom it may concern:

Be it known that I, ABRAHAM B. GREENWALT, of Millersville, in the county of Lancaster and State of Pennsylvania, have originated and produced a new and original Design for a Toy-Wheelbarrow Frame, the same consisting in a frame formed from a single piece of wire, bent as shown in the accompanying illustration.

In the drawing, A A' are the legs, B B' the sides, C C' the wheel-supporting portions, D E D' the back, and F F' the handle, of the wheelbarrow-frame.

In my new design the legs of the wheelbarrow-frame are each of a single thickness of wire, the handles are of double thickness, the sides and back are of a single thickness, and the wheel-supporting portions are each of dou-

ble thickness of wire, and provided with openings in the ends thereof for supporting the wheel of the barrow, and the entire frame is of a single piece of wire, bent to form the design shown.

What I claim as my new design, and desire to secure by Letters Patent, is—

The design for a toy-wheelbarrow frame having the legs and frame of back of a single thickness of wire, and the wheel-supporting portions and handles of a double thickness of wire, substantially as described, and shown in the accompanying illustration.

A. B. GREENWALT.
